UNITED STATES PATENT OFFICE.

JOSEPH A. SALZMAN, OF TOLEDO, IOWA.

DESIGN FOR AN EMBLEM.

46,653.

Specification for Design.

Patented Nov. 17, 1914.

Application filed September 21, 1914. Serial No. 862,813. Term of patent 7 years.

To all whom it may concern:

Be it known that I, JOSEPH A. SALZMAN, a citizen of the United States, residing at Toledo, in the county of Tama and State of Iowa, have invented a new, original, and ornamental Design for an Emblem, of which the following is a specification, reference being had to the accompanying drawing, forming part thereof.

Figure 1 is a face view of an emblem, embodying my design. Fig. 2 is an edge view thereof.

I claim:

The ornamental design for an emblem, as shown.

JOSEPH A. SALZMAN.

Witnesses:

C. J. BELKRAF,

C. L. CUPPEN.
